UNITED STATES PATENT OFFICE.

JAMES ERNEST MORTON, OF WEST LAFAYETTE, INDIANA, ASSIGNOR OF ONE-HALF TO
JAMES H. McVEETY, OF MEMPHIS, TENNESSEE.

AUTOMOBILE PARKING MACHINE.

Application filed July 9, 1925. Serial No. 42,527.

To all whom it may concern:

Be it known that I, JAMES E. MORTON, a citizen of the United States, and a resident of West Lafayette, in the county of Tippecanoe and State of Indiana, have invented a new and Improved Automobile Parking Machine, of which the following is a full, clear, and exact description.

This invention relates to automobile parking machines, an object of the invention being to provide an improved construction and arrangement of tower having improved mounting for supporting chains with platforms connected thereto, each platform 10 adapted to receive and support an automobile and capable of operation so as to move the automobile up and down in two different columns so that a minimum of ground space is required for the accommodation of 15 a large number of cars.

A further object is to improve upon the construction set forth in my Patent No. 1,555,692.

With these and other objects in view, the 20 invention consists in certain novel features of construction and combinations and arrangements of parts, which will be more fully hereinafter described and pointed out in the claims.

Figure 1 is a fragmentary perspective view, showing the lower portion of my improved machine;

Figure 2 is a similar view, showing the upper portion of the machine;

Figure 3 is a sectional or broken perspective view, partially diagrammatic, illustrating the arrangement of supporting chains and the manner of connecting the platforms thereto;

Figure 4 is a broken view in longitudinal section through the machine;

Figure 5 is a fragmentary view in section on the line 5—5 of Figure 4;

Figure 6 is a fragmentary view in section 45 on the line 6—6 of Figure 4;

Figure 7 is a view in horizontal section on the line 7—7 of Figure 4;

Figures 8 and 9 are fragmentary views in 50 elevation, illustrating portions of different chains and the manner of coupling or con-

necting the platform supporting fingers thereto;

Figure 10 is a top plan view of one of the car supporting platforms;

Figure 11 is a somewhat enlarged view, 55 showing one of the chain guides slightly modified, this modification being of course applicable to all of the chain guides.

A represents my improved tower, which is of skeleton form and which may have the 60 parts rigidly or removably connected, whereby the tower may be readily taken down and moved from place to place and assembled at the point of use.

The tower A is of general rectangular 65 form in cross section and may be of any desired height, and is made up of four vertical posts 1 at the corners of the tower connected by horizontal bars 2 and by diagonal bracing 3.

A top frame 4 is fixed on the tower and is made in much the same manner as the main portion of the tower, and gusset plates 5 connect the angles of the framework at the 70 point of connection between the main tower and the upper frame and also located at the corners of the base of the tower and serve to connect a frame or base work 6 to the tower.

Of course I do not limit myself to any 75 particular form of framework as this may be made of angles, channels and other well known types of steel bars, but desire to cover broadly the idea of an open framework tower which may be readily assembled and 80 taken apart, the several parts being either bolted or riveted in accordance with the desire of the trade.

For purposes of description I shall refer 85 to the tower as having front and rear ends, that portion of the tower where the cars enter being known as the front and the opposite side or end of the tower the rear.

The tower extends through an opening 7 in a floor or platform 8 so that the cars 9 90 may be run from the floor 8 onto the machine or into the tower, as will more fully hereinafter appear.

At the front and rear of the tower a pair 95 of spaced uprights 10 is secured and these 100

spaced uprights 10 as well as the posts or uprights 1 at the corners of the tower constitute box-like casings, suitably slotted for the reception of the several runs of the chains which will be described.

At the upper and lower ends of the tower horizontal channels 11 and 12, respectively, are provided for the upper and lower runs of the chains, and the lower channels 12 are capable of vertical adjustment so as to adjust the tension of the chain.

Convenient means for adjusting is illustrated in Figure 1 where bolts 13 are projected through slots 14 in the plates 5 and 15 are secured by nuts 15. In any event I desire to provide some means which will secure the lower channels 12 at a desired vertical adjustment so that the chains are maintained relatively taut, and I do not wish to be limited to the specific manner of adjustment.

Any desired number of car supporting platforms 16 may be provided and these platforms, one of which is illustrated in Figure 10, have supporting fingers at both ends, one supporting finger 17 at one end being longer than the other supporting finger 18 at the same end, and said longer fingers being diametrically disposed with relation to the shorter fingers.

On top of each platform I provide an upwardly projecting receptacle 19 having tapering or inclined ends, so that when the car is on the platform this receptacle will catch any grease which may fall from the car and prevent the same from passing to the cars below, and furthermore will guide the cars on and off the platform.

The platforms may be strengthened and 40 braced in any desired manner, but I have illustrated for the purpose a pair of angle irons 20 which are secured together intermediate their ends and flare outwardly at their ends and are secured to transverse 45 strengthening bars 21. Each platform at both ends is provided with an upstanding plate 22 on which a numeral may be provided so that the owner of the car can receive a check which will indicate on what 50 platform his particular car is supported.

Between the platforms at the floor elevation a bridge 23 is located so that persons may walk onto this platform and enter the car when the car is at the platform.

My invention has particularly to do with the arrangement of chains that support and the manner of connecting the platforms to the chains, all of which will now be described in detail.

First, I would state that I employ both at the front and at the rear of the tower three separate and distinct endless chains which may be distinguished as follows: 24 represents the central chain which is located intermediate the sides of the tower and

is supported on sprocket wheels 25 at the upper and lower ends of the tower, and the runs of this chain are housed in the box-like uprights 10.

At the front and rear of the tower, in addition to the chain 24, a complete run chain 26 is located. I term this chain "complete run" in order to distinguish it from the center chain 24 and also to distinguish it from a third chain 27 which I shall term a "half length" chain. The full length chain 26 passes over three sprocket wheels 28, 29 and 35 at the top and at the bottom of the tower, and the vertical runs of this chain are housed within the corner posts or box-like structures 1 so that it takes a track path throughout the full area of the front and rear, and for this reason I call it a "full length" chain.

At the front and rear the half length chains 27 are also provided with and are supported on sprocket wheels 31 and 32 at the top and bottom of the tower. The vertical runs of these chains 27 are mounted in one of uprights 1 and one of the box-like uprights 10, respectively, and the chain 27 at the front is diagonally disposed with relation to the chain 27 at the rear.

The long finger 17 at one end of each platform 16 is permanently connected to a link 33 of the half length chain 27 at the front of the tower, and the other long finger 17 at the other end of the platform is permanently connected to a similar link 33 of the half length chain 27 at the rear of the tower.

All the other chains have hook-like links 34 for the reception of the shorter fingers 18 of the respective platforms. These links 34 give sufficient bearings to the fingers to provide a firm support for the platform, but they are so arranged as to allow the fingers to ride into and out of engagement with the chains as the platforms move horizontally at the upper and lower ends of the tower so as to be transferred from one vertical column of the tower to the other.

While of course I do not limit myself to any particular means for transmitting power to move the several chains, I have illustrated in Figure 2 an electric motor 35 mounted on top of the tower and connected by a gear train 36 with a shaft 37 on which the sprocket wheels 25, 29 and 31 are secured. All of the sprocket wheels are of the same size so that a uniform movement is imparted to the chains when the machine is operating.

As all the platforms operate precisely alike the description hereinafter of one platform will apply alike to all. Reference is made particularly to Figure 3 of the drawings. Assuming that the left-hand platform is moved upwardly until it reaches its highest position it will then be moved horizon-

- tally to the right of Figure 3 and all four corners of the platform will be supported. The reason is this: that the channels 11 at the top of the tower will support the horizontal runs of the chains and while the shorter fingers 18 have a tendency to leave the chain 26 they cannot move downwardly because they are housed within the channel 11.
- 10 The longer fingers 17 which have been connected to one run of the center chain 24 will leave this chain and move to the right and into the bearings or hook-shaped links 34 of the chain 26, so that while the left-hand runs of the chains 26 will support the left-hand column of the platforms either in their upward or downward movement these platforms when moved to the right column will have their shorter fingers supported by
- 15 the right-hand runs of the chains 24. The center chain 24 will support the fingers adjacent thereto both in their upward and downward movements but will permit their release, being transferred horizontally from
- 20 one column to the other, and the longer fingers of each platform will be permanently connected to the half length chains 27.
- It will thus be noted that while the platforms can be moved upwardly and downwardly at the will of the operator when said platforms reach either the upper or the lower end of the tower, they are transferred laterally from one column to the other and all four corners of the platform are supported at all times.
- 25

- 30 While I have described the movement of the platforms at the top of the tower, it is to be understood that their movements at the bottom or lower end of the tower are precisely the same, and that the channels 12, illustrated in detail in Figure 6, will give support to the fingers, which might have a tendency to move away from their chains during such horizontal or lateral movement.
- 35 The vertical box-like guides 1 and 10 at the front and rear of the tower prevent any lateral swinging movement of the platforms, and I may provide in these guides adjustable wear plates 38 having set screws
- 40 back of the same to adjust them toward and away from the chains so as to take up wear and prevent lateral or wabbling movement of the chains.

- 45 In operation the cars 9 are run onto the platforms 16 when the latter are at the floor level 8 and the motor 35 is controlled to cause said platforms to raise or lower until the entire tower is full of cars. Any particular car can be removed at any time
- 50 desired by causing the mechanism to operate to bring that car to the floor level, and the operator can walk out on the bridge 23 and into the car and drive away.

- 55 It will be noted that the runs of the chain are closely confined in their box-like

guides, and in the event that the chain breaks there would be a piling up of the chain to stop the movement of the platform and prevent accidents.

Various slight changes and alterations 70 might be made in the general form of the parts described without departing from my invention and hence I do not limit myself to the precise details set forth but consider myself at liberty to make such slight 75 changes and alterations as fairly fall within the spirit and scope of the appended claims.

I claim:

1. An automobile parking machine, including a skeleton tower, a plurality of endless chains at two sides of the tower, two columns of car receiving platforms mounted on said chains, means permitting the platforms to move laterally at the upper and lower ends of the tower, a floor through which the tower projects and from which cars may be driven onto the platform, and a bridge in the tower located at the floor level between the two columns of the platform.

2. An automobile parking machine, including a skeleton tower, a plurality of endless chains at two sides of the tower, two columns of car receiving platforms mounted on said chains, means permitting the platforms to move laterally at the upper and lower ends of the tower, and box-like slotted vertical columns on the tower receiving and housing the vertical runs of the chains.

3. An automobile parking machine, including a skeleton tower, a plurality of endless chains at two sides of the tower, two columns of car receiving platforms mounted on said chains, means permitting the platforms to move laterally at the upper and lower ends of the tower, box-like slotted vertical columns on the tower receiving and housing the vertical runs of the chains, and adjustable means engaging the vertical runs of the chains.

4. An automobile parking machine, including a skeleton tower, a plurality of endless chains at two sides of the tower, two columns of car receiving platforms mounted on said chains, and means permitting the platforms to move laterally at the upper and lower ends of the tower, each platform having a grease receptacle thereon and having fingers at the four corners thereof engaging the respective chains.

5. A machine of the character described, including a tower, three sets of chains at the front and rear of the tower, sprocket wheels supporting said chains, one of each set of chains constituting a central chain intermediate of the sides of the tower, one of said chains substantially conforming in length to the contour of one end of the tower

whereby the vertical runs of said chains are at the outer columns of the tower, and the third of each set substantially half the size of the last-mentioned chain and located at one side of the tower only, two columns of platforms, and fingers at the four corners of the platforms, certain of said

fingers permanently connected to certain of the chains and others of the fingers removable connected to the other chains, and horizontal guides supporting the fingers in lateral movement of the platform at the upper and lower ends of the tower.

10

JAMES ERNEST MORTON.
